GOLF CLUB COVER

John S. Runyan, San Clemente, Calif.

Application December 6, 1948, Serial No. 150,005

Term of patent 7 years

(Cl. D34—5)

To all whom it may concern:

Be it known that I, John S. Runyan, a citizen of the United States and a resident of the city of San Clemente, county of Orange, State of California, have invented a new, original, and ornamental Design for a Golf Club Cover, of which the following is a specification, reference being had to the accompanying drawing, forming a part hereof, in which:

Fig. 1 is a top plan view of a cover for a golf club embodying my new design;

Fig. 2 is a side elevational view;

Fig. 3 is an end elevational view of the left end of Fig. 1;

Fig. 4 is an end elevational view of the right end of Fig. 1; and

Fig. 5 is a plan view of the bottom thereof.

I claim:

The ornamental design for a golf club cover, substantially as shown.

JOHN S. RUNYAN.
